PISTON

John Flammang, St. Louis, Mo., assignor to The
Sterling Corporation, St. Louis, Mo., a corpora-
tion of Delaware

Application February 15, 1937, Serial No. 125,756

1 Claim. (Cl. 309—11)

This invention pertains to pistons and more particularly to trunk type pistons constructed of thermo-expansible metal such as aluminum, or its alloys, magnesium and the like, having a high coefficient of thermal expansion.

One of the objects of this invention is to provide a piston of the character described which will function in a cylinder through various ranges of temperature and compensate automatically for expansion.

Further objects will appear from the following description taken in connection with the accompanying drawing, in which:

Figure 1 is a side view illustrating one form of piston to which this invention may be applied.

Figure 2 is a longitudinal section through the wrist pin axis of the piston shown in Figure 1.

Figure 3 is a sectional view of an engine cylinder illustrated with a piston therein constructed in accordance with this invention, said piston being seen in bottom view, and

Figure 4 is a fragmentary side view similar to Figure 1, illustrating another form of piston to which this invention may be applied.

Referring to the drawing the piston comprises a head 1 and a skirt indicated generally at 2. Wrist pin bosses 3 are provided. These bosses are connected to the head 1 by a stiff structure including one or more longitudinal ribs 4 extending from the upper portion of each wrist pin boss to the inner side of the head. Similarly, one or more reinforcing ribs 5 may be arranged to extend across the head on the interior thereof. The structure thus described including the head, the ribs 4 and the wrist pin bosses 3 is made stiff and rigid so as to provide a strong frame structure adapted to deliver the thrust of the gas explosion to the connecting rod.

The skirt 2 is separated from the head 1 adjacent the two thrust faces. The thrust face 40 which takes the thrust of the power stroke, shown in interior view in Figure 2, may or may not be separated from the head by a horizontal slot or gap 6. This face is solid or uncut longitudinally, while the opposite face, shown in Figure 1, is separated from the head 1 by a slot or gap 7, and in addition is cut by a longitudinal slot 8, extending up into and communicating with the gap 7. In some cases it may be desirable to extend the slot 8 clear to the open end of the piston skirt as shown in Figure 1. In other cases this slot may be terminated at a point 9 as shown in Figure 4, short of the open end of the skirt.

This cutting of the circumferential slot or slots in the piston isolates the skirt from the head in

the regions of the thrust faces and the skirt is "relieved" in the regions of the bosses 3. Such relief may consist simply in cutting back or otherwise forming the outer surface of the skirt 5 so as to have a clearance of sufficient amount so that those portions will not press against the cylinder wall when the piston expands. In the piston illustrated this takes the form of recesses opposite the bosses provided by inwardly spaced webs 14 connecting the skirt with the bosses. In order to provide still more ample relief at the top, the relieved portions may be extended from the regions opposite the bosses around toward one or both thrust faces so as to approach, to a greater or less extent, the bearing axis of the bearing or thrust face. In the form of piston illustrated in the drawing this relieved portion is formed to approach more closely, to the bearing axis at the head end of the skirt than therebelow, thereby providing the so-called "Keystone" relief.

25 A bridge 11 spans the slot 8, preferably just below the circumferential slot 7. The middle portion of this bridge is relatively thin so as to be comparatively flexible, while each end of the bridge has an anchorage 12 having an extended connection with the skirt on the inside and, therefore, relatively rigid. A gap 13 may be provided in the bridge, and this gap as well as the bridge 15 itself, is formed in the casting when made in the usual way, namely, in a permanent mold. After the piston has been cast, the circumferential and vertical slots are formed and the gap 13 permits the saw or slotting device to travel through the skirt at the top. In the complete piston, therefore, the corners 10 will be supported.

The piston is made in the usual manner with the head provided with the usual ring grooves 18 of smaller diameter than the skirt. This skirt may also be given the usual taper so as to be slightly smaller at the top than at the bottom.

When such a piston is placed in the cylinder and subjected to the heat of the gases, the head will, of course, expand radially in all directions. 45 This radial expansion of the head is transmitted to the skirt only in the regions of the wrist pin bosses where, however, the skirt is relieved to permit such expansion. Such radial expansion of the head is not transmitted to the region of the thrust face between the bosses, because of the isolation brought about by the circumferential slot. As a result, therefore, the isolated thrust face is drawn in so as to compensate for expansion on that diameter, while expansion along the line of the wrist pin bosses has been com-

pensated for by the relief. Such drawing in of the thrust face is permitted because of the bridge which, however, prevents undue flexure of the skirt at the top, particularly at the corner and, therefore, insures quiet operation. It will be understood that where the head is also isolated from the skirt at the unslotted face, there will be a drawing in on that face also as expansion takes place along the line of the bosses.

It will be obvious that various changes may be made in the details of construction, within the scope of the appended claim, without departing from the spirit of this invention. It is understood, therefore, that the invention is not limited to the specific details shown or described.

Having thus described the invention, what is claimed is:

A trunk piston of thermo-expansible material having a head, a skirt, and wrist pin bosses connected to the head, said skirt having cylinder-bearing thrust faces and having relieved areas

adjacent said wrist pin bosses and between said thrust faces to permit thermal expansion in the direction of the wrist pin axis, one of said thrust faces being separated from the head by a slot 5 extending horizontally between said relieved areas adjacent the top of the skirt, said thrust face having another slot extending vertically and medially thereof downwardly from said horizontal slot defining separate bearing corners adjacent the junction of said horizontal and vertical slots, and a bridge member anchored interiorly to the respective bearing corners and bridging the vertical slot adjacent the horizontal slot, and interior anchorage between said bridge and the 10 respective bearing corners being circumferentially extended substantially across the thrust face, said bridge member being constructed and arranged to prevent undue flexure of the separate bearing corners.

JOHN FLAMMANG.
